Primary Examiner — April Rivas*Assistant Examiner* — Tia Ruth-Renee Polidori(74) *Attorney, Agent, or Firm* — Birch, Stewart, Kolasch & Birch, LLP(57) **CLAIM**

The ornamental design for a gas cooktop as shown and described.

DESCRIPTION

FIG. 1 is a front perspective view of our new design for a gas cooktop;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a partial enlarged view of the area '8' as identified in FIG. 1.

The broken lines depict portions of the gas cooktop that form no part of the claimed design.

1 Claim, 8 Drawing Sheets(56)
